N. PAPPARODIS

ENVELOPE

Filed March 18, 1922

By Matthews & Matthews
Attorneys

UNITED STATES PATENT OFFICE.

NICK PAPPARODIS, OF BEAVER FALLS, PENNSYLVANIA.

ENVELOPE.

Application filed March 18, 1922. Serial No. 544,825.

To all whom it may concern:

Be it known that I, NICK PAPPARODIS, a subject of the King of Greece, residing at Beaver Falls, in the county of Beaver and State of Pennsylvania, have invented certain new and useful Improvements in Envelopes, of which the following is a specification.

The present invention relates to improvements in envelopes, although the invention will find equal application to paper boxes or to containers generally made of paper or light material, in which the use of glue, paste or other adhesive now generally employed to seal the envelope flap is dispensed with and the various flaps of the envelope are securely closed so as to prevent unauthorized inspection or removal of the contents and to avoid the opening of the envelope or container without mutilating the same and plainly showing the fact that the mail matter has been tampered with.

It is an object of the invention to secure a permanently locked inclosure for mail matter and the like whereby such matter may be transported in the mails with safety and may be used for the transport of first class matter without requiring an adhesive flap to be moistened, thus avoiding the annoyance and inconvenience incident to the sealing of such flaps, but on the other hand the invention permits in a simple and inexpensive paper structure of the closing and the effectual locking of the flaps and the mail matter contained therein in a quick and convenient manner, and the invention further will allow of the opening of the inclosure by the authorized addressee in a much quicker manner attended with less inconvenience than the present envelopes.

With the foregoing and other objects in view, the invention will be more fully described hereinafter, and will be more particularly pointed out in the claim appended hereto.

In the drawings, wherein like symbols

refer to like or corresponding parts throughout the several views,

Fig. 1 is a plan view of the blank from 50 which one form of the invention is made;

Fig. 2 is a reverse face view of this envelope closed;

Fig. 3 is a plan view of a slightly modified form of blank; 55

Fig. 4 shows this blank closed in envelope form;

Fig. 5 is a cross section taken on the line 5-5 in Fig. 4;

Fig. 6 is a fragmentary perspective view 60 showing the manner of inserting a tongue within one of the improved slots; and,

Fig. 7 shows a slightly modified form of blank over Fig. 3.

Referring more particularly to the drawings, and for the present to Figs. 1 and 2 thereof, 1 designates the body portion of an envelope having the lateral flaps 2 and 3 and the end flaps 4 and 5 all made out of the same blank and from a sheet of appropriate paper or other flexible material admitting of the lateral flaps being bent upon lines of flexure indicated at 6 and 7 and the end flaps upon lines of flexure 8 and 9 to enable the device to assume the closed position shown in Fig. 2. 65

The lateral flaps 2 and 3 are first folded over upon the body 1 and thereafter the lower end flap 5 is bent upon its line of flexure 9. Lastly, the opposite end flap 4 70 is folded over upon the line 8. The lateral flaps 2 and 3 are provided with diagonal lower edges 10 and 11 which are the result of removing lower portions of these flaps, the diagonal lines conforming substantially 75 but not identically with the lower edges of the bottom flap 5. The end flaps 4 and 5 are substantially triangular and the edges of the flap 5 overlap to a suitable extent the edges 10 and 11 of the lateral flaps. 80

The flaps 2 and 3 and in the lower flap 5 are produced slots 12, 13 and 14 for receiving respectively, tongues 15, 16 and 17. The tongue 15 is produced upon the apex of the 85

upper flap 4, while the companion tongues 16 and 17 are upon the edges of the lower triangular flap 5 and equidistant from the apex point of this flap. They are thus caused to extend on diagonal lines and are positioned to be received into the slots 13 and 14 when the envelope is assembled as indicated in Fig. 2. Now each of the tongues is provided with a T-head made up of lateral ears 18 and 19 which are adapted to be folded over above or beneath the end portion of the tongue as indicated in Fig. 7, just prior to inserting the tongues in the slots. The outer corners of the ears are also preferably cut off as indicated at 20 to better serve in the insertion of the tongues and in the holding of them in place later.

Each slot is made with a straight wall 21 next the tongue which is to fit therein into, and with an opposite edge wall which conforms to a compound curve or a substantially V-shape having a central apex 22 which recedes farthest from the straight edge 21 and is approximately centrally located with reference to the length of the slot. From this apex rounded edge portions 23 and 24 extend in divergent relation until the outer extremities thereof merge with the ends of the straight wall 21. There is thus left in the center of the slot a relatively large opening for the easy insertion of a corner of one of the tongues 15. This tongue is canted as indicated in Fig. 6 to bring one corner portion to approach the apex 22 where it will give the corner the greatest freedom and opportunity to enter the slot. Having once caught the corner under the apex, the tongue is simply pushed sidewise causing its side edge to ride along the curved edge portion 24. Due to the curvature of this portion toward the opposite straight wall 21, the tongue will enter deeper into the slot or rather the sides of the slot will envelope more of the corner portion of the tongue and thus make the engagement more secure as the action progresses. This curved wall will also induce an easy sliding of the tongue thereacross and into place, and having arrived at the end of the slot, the opposite corner of the tongue is readily inserted beneath the other curved edge portion 23. The curvature causes the central part of the portions 23 and 24 to bulge out so that a corner of the tongue may be readily inserted therebelow.

After the tongue is securely engaged with in the slot and pushed home therein, the ears 18 and 19 may be opened so as to lock the same in place. The flat character of the envelope or container will insure that these ears remain in the open position and against escape from the slot. The envelopes may be assembled for sale with the tongues 16 and 17 already engaged with the flaps

2 and 3, leaving only the upper end flap 4 free for the insertion of mail matter. All that a user is required to do under these circumstances is to insert the latter and to then engage the tongue 15 with a slot 12 which is easily accomplished particularly by virtue of the conformation given the slot walls. The device is then for all purposes locked and unauthorized persons are not enabled to tamper with the contents without plainly showing the effects of such tampering.

Referring to Figs. 3 and 4, the device herein shown consists of a body portion 25 having lateral flaps 26 and 27, a lower end flap 28 and an upper end flap 29 all foldable upon the body as in the former case. In this instance, the lateral flaps are substantially the same size as the body portion and they overlap to a great extent when folded. Both lateral flaps and the lower end flap 28 are all provided with slots as shown which register when folded. A T-headed tongue 30, projecting outwardly from the upper end flap 29, is adapted to engage through all three of the slots and thus hold the device locked, the T-head being spread out upon the innermost portion of the envelope, as indicated in Fig. 5.

In Fig. 7 is shown, a very similar form of envelope with parts similarly numbered, but in this instance, the slots 31 are made with straight sides.

In view of the foregoing, it will be appreciated that I have produced an extremely simple and inexpensive envelope in which the use of an adhesive flap is entirely done away with without however making it more difficult to close the flap or flaps and without rendering the enclosure more capable of being tampered with.

It is obvious that various changes and modifications may be made in the details of construction and design of the above specifically described embodiment of this invention without departing from the spirit thereof, such changes and modifications being restricted only by the scope of the following claim:

What is claimed is:

An envelope having a body portion and a number of flaps extending therefrom and adapted to be folded over upon the body portion and in overlapping relation to provide an enclosure, one flap having a tongue thereon and another flap having a slot adapted to receive the tongue, said tongue being substantially of the same width as the length of the slot and being substantially rectangular at its end, said slot having an inner straight wall and having in its outer wall a substantially V-shaped opening intermediate the ends of the slot, the opposite edges of said opening flaring and being rounded toward the straight wall

and merging into the slot at the opposite ends thereof, whereby upon engagement of a corner of the tongue in said opening against any part of said curved edges and upon the lateral shifting of the tongue the sides of the slot will envelope more of the corner portion of the tongue as the shifting

action progresses and the tongue will be brought to a stop and held at the closed end of the slot.

10

In testimony whereof I affix my signature.

NICK PAPPARODIS.
